UNITED STATES PATENT OFFICE

WILLIAM A. EDWARDS, OF CHICAGO, ILLINOIS, ASSIGNOR TO STEWART-WARNER CORPORATION, OF CHICAGO, ILLINOIS, A CORPORATION OF VIRGINIA

RADIATOR SHUTTER CONTROL

Application filed February 21, 1929. Serial No. 341,607.

The purpose of this invention is to provide an improved construction for automatically regulating atmosphere access to the radiator of an automobile engine according to the engine requirement of cooling to be effected by the atmosphere circulation through the radiator. It consists in the elements and features of construction shown and described as indicated in the claims.

10 In the drawings:

Figure 1 is a diagrammatic view showing,—as in side elevation, an apparatus embodying this invention in its relation to the shutter system of the radiator to be controlled thereby.

15 Figure 2 is a similar view illustrating another specific form of the invention.

Figure 3 is a perspective view designed to show the invention in either of the species 20 illustrated in the preceding figures, having all parts of the apparatus assembled in the radiator front which contains the shutter system.

In apparatus and devices hitherto commonly employed for the general purpose of automatically regulating atmosphere access to the radiator of an internal combustion engine, for preventing over-heating, no attention,—or only minor attention,—seems to 25 have been given to the matter of conserving the heat for maintaining effective running conditions during alternating travel and halting of the vehicle. Also in these commonly employed structures, reliance is placed 30 wholly on utilizing the same temperature changes of the engine for effecting the adjustment of the shutter; which results in the shutter remaining wide open when the car is halted and stands, perhaps, facing cold wind 35 which rapidly cools the radiator before the shutter becomes closed by the lowering of the temperature of the engine, thus wasting a large amount of energy which might be 40 conserved by proper means, avoiding the delay in closing the shutter under such circumstances.

The present invention utilizes for operating the shutter, engine pressures which vary with running of the engine, and which cease 45 when the engine stops, the degree of these

pressures having been found to correspond very closely with the requirement of the engine for the cooling function of the radiator, to the extent that that function depends on atmosphere access to the radiator as controlled by the shutter; and the decline of these engine pressures upon stopping of the engine being so much more rapid and prompt than the lowering of the engine temperature, 55 that there is avoided the undesirable delay in closing the shutter after the vehicle stops, which constitutes ground of criticism of the common methods as above pointed out.

Inasmuch as any opening of the shutter 60 may usually be dispensed with when the engine is running at idling speed without load, and up to a certain minimum speed, and also under conditions of extreme atmospheric 65 temperature tending to cool the engine sufficiently without any atmosphere circulation 70 through the radiator, it may be found desirable in some types of engine and engine housing and protective casing, to associate with the means indicated operable by engine pressures, elements operated by change in engine 75 temperature for establishing the connection for operating the shutter by the engine pressures, when, notwithstanding the sufficiency of these pressures, the engine is so cooled by other means than the atmosphere circulation through the radiator, as 80 not to require that circulation in any degree.

For utilizing the engine pressure selected 85 for the purpose, whether for example, the superatmospheric pressure of the exhaust manifold, or the subatmospheric pressure of the intake manifold, connection is made to any form of expansible and reducible chamber—as a piston cylinder—the movable member of the wall of such chamber, whose movement causes or is caused by the enlargement 90 and reduction of the fluid capacity of the chamber, is connected by any suitable and conveniently arranged means with the shutter-adjusting means of the radiator; and 95 when it is considered desirable to limit the engine pressure control of the shutter adjustments to a predetermined engine temperature, so that the shutter will not be adjusted by the engine-pressure-operated 100

means, unless the engine temperature is up to a predetermined degree, the temperature-responsive element positioned for being affected by engine temperature is interposed or operatively connected with a part which is interposed, in the operating connection from the movable member of the expandable and reducible chamber to the shutter-operating means, so as to enable the expansion and contraction of said chamber to operate the shutter-adjusting means.

Referring to the drawings:—The radiator shutter system is indicated as to its entirety at A, the individual shutter vanes being each indicated at *a*, and shown, as in the customary construction, connected by an operating rod, 20, which is attached to the lever arms, 21, provided at one end of the respective shutter vanes, and upheld normally by a spring, 23, at position for holding the shutter vanes closed, said operating rod being connected at its upper end by a link, 22, with an arm, 31, of a bell crank lever whose other arm, 30, is connected to the forwardly protruding end of the stem, 41, of the temperature-responsive device, which may be of any construction for varying the distance between its front and rear terminals, according to temperature change. The particular structure illustrated consists of a closed and resiliently expandible air chamber, 40, which, for convenience of mounting and connection and guidance of its connections, is enclosed in a casing, 42, and besides the forwardly projecting stem, 41, protruding from and obtaining sliding guidance in the forward head of the casing, 42, has a similar stem, 43, projecting from its rear head and out through the rear head of the casing, 42, in rear of which it carries a terminal disk, 44.

For affording means for utilizing engine pressure to operate the shutter-adjusting means by thrust against the rear terminal of the stem, 43, there is mounted in any convenient position on any fixed part of the engine structure,—as on a bracket, 50, secured to the engine body,—a piston cylinder, 51, axially aligned with the resiliently expandible and contractible air chamber, 40, and having a piston, 52, reciprocable in, and having a stem protruding from, the forward end of the cylinder, and provided with a disk terminal, 55, adapted by the alignment of the two reciprocable parts to collide with the disk, 44, when the piston is thrust forward in the cylinder a sufficient distance by the engine pressure.

The piston cylinder, 51, is connected at its rear end by a duct, 56, with a source of engine pressure, the connection shown in Figure 1 being intended to be understood as either with the exhaust manifold or with the head of a selected cylinder of the engine, so as to conduct super-atmospheric pressure

to the cylinder, 51, behind the piston for forcing the latter forwardly.

The parts are dimensioned and mounted with respect to each other so that with the resilient air chamber in its normally collapsed or unexpanded condition, and at the position in the casing, 42, at which it is held by its connection with the shutter system when the latter is held normally closed by the action of the spring, 23, and with the piston, 52, also at its normal position when the engine is not running, the two terminal disks, 44 and 55 are separated a distance at least equal to the full stroke which the piston, 52, can make in the cylinder, 51, under the engine pressure when the engine starts.

But this distance does not exceed the range of expansibility of the air chamber, 42, which is mounted against the engine body so as to experience expansion by engine heat when the engine is running. Accordingly, when the engine starts, and the pressure from the exhaust manifold or from an engine cylinder, entering the cylinder, 51, causes the piston to move forwardly in the cylinder, the terminal disk, 55, will encounter the terminal disk, 44, when the engine has been running long enough to become heated, and heat the expandible air chamber so as to cause that device to expand and thrust its rear stem rearward into encounter with the terminal of the piston stem.

The parts are dimensioned so that at the predetermined temperature of the expandible and contractible air chamber, 42, which temperature it may derive from the engine, the thrust of the piston stem against the stem of the air chamber expanded by the engine heat, will cause the two elements which constitute the connection of the piston to the bell crank lever to operate as a unit for actuating the bell crank lever in opposition to the spring, 23, for operating the shutter. And it will be understood that the degree of opening of the shutters will be determined by the degree of pressure operating in the cylinder, 51. And since the pressure, whether derived from the exhaust manifold or from one cylinder of the engine, corresponds approximately to the tendency of the running to heat the engine, the radiator shutter will be opened more or less correspondingly to the rise of engine temperature beyond the predetermined degree at which the resulting expansion of the resilient air chamber, 42, bringing its terminal into collision with the terminal at the piston stem, causes the two elements to act as a unit for transmitting the engine pressure on the piston, 51, to the bell crank lever.

In the form shown in Figure 2, the engine pressure utilized is the sub-atmospheric pressure derived from the engine intake manifold, which as a negligible quantity brings into operation atmospheric pressure as the

positive force for operating the piston. And accordingly in this construction the pressure connection to the cylinder indicated by the duct, 56, is made at the rear end instead of the forward end of the cylinder for obtaining the same rearward thrust of the piston as in the construction of Figure 1 is obtained by the super-atmospheric pressure connection at the forward end of the cylinder.

10 I claim:

1. In combination with means regulating atmosphere access to the exterior of the radiator of an internal combustion engine, a device having an expansible and contractible chamber arranged to be connected with a cylinder of the engine served for access to said chamber of fluid pressure from the engine cylinder, and for building up pressure in said chamber, said chamber having a part movable by the pressure built up in the chamber, and operating connections from said movable part to said first mentioned means arranged for enlarging said atmosphere access correspondingly to said built up pressure beyond a predetermined minimum of atmosphere access and a corresponding predetermined minimum of built up pressure, said operating connections comprising two relatively movable parts, one of which is positively connected with the engine-pressure-influenced element for positive movement by the movable part thereof, the other being positively connected with the atmosphere-access-regulating means of the radiator; means for disengageably connecting said two relatively movable parts to cause the first to actuate the second, and temperature-responsive means exposed to engine temperature arranged for engaging said two parts for movement of the second by the first upon predetermined temperature-caused-action of said temperature-responsive part.

2. In combination with means for regulating atmosphere access to the exterior of an engine radiator, a device comprising an expansible and contractible chamber arranged for connection with a cylinder of the engine served for access to said chamber of fluid pressure from the engine cylinder, said chamber having a part movable by the pressure admitted to said chamber; an element operatively connected with the atmosphere-access-regulating means of the radiator comprising a part mounted for movement into and out of position for encounter with the movable part of said expansible and contractible chamber and comprising a temperature-responsive member which is mounted for exposure to engine temperature and by which said part is carried in the temperature-responsive movement toward and from the movable part of the expansible and contractible chamber.

3. In combination with means for regulating atmosphere access to the exterior of an

engine radiator, a temperature-responsive element mounted for exposure to engine temperature and operatively connected with said atmosphere-access-regulating means, a part carried by said temperature-responsive element for movement by said element in the temperature-responsive movement of the latter, a device comprising an expansible and contractible chamber arranged for connection with a cylinder of the engine served for access to said chamber of fluid pressure from the engine cylinder, said chamber having a part movable by the pressure admitted to said chamber, said movable part and the part carried by the temperature-responsive element being positioned for encounter with each other in the movement of the first mentioned movable element due to engine pressure and the movement of the second mentioned movable element due to rise of engine temperature beyond a predetermined degree.

4. In combination with means for regulating atmosphere access to the exterior of an engine radiator, a temperature-responsive element mounted for exposure to radiator temperature and operatively connected with said atmosphere-access-regulating means, a part carried by said temperature-responsive element for movement by said element in the temperature-responsive movement of the latter, a device comprising an expansible and contractible chamber arranged for connection with a cylinder of the engine served for access to said chamber of fluid pressure from the engine cylinder, said chamber having a part movable by the pressure admitted to said chamber, said movable part and the part carried by the temperature-responsive element being positioned for encounter with each other in the movement of the first mentioned movable element due to engine pressure and the movement of the second mentioned movable element due to rise of radiator temperature beyond a predetermined degree.

5. In an engine having a circulatory cooling system comprising a radiator, in combination with means for regulating atmosphere access to the exterior of the radiator, a temperature-responsive element mounted for responding to change of temperature of the circulatory cooling system of the engine and operatively connected with said atmosphere-access-regulating means, a part carried by said temperature-responsive element for movement by said element in the temperature-responsive movement of the latter, a device comprising an expansible and contractible chamber arranged for connection with a cylinder of the engine served, for access to said chamber of fluid pressure from the engine cylinder, said chamber having a part movable by the pressure admitted to said chamber, said movable part and the

part carried by the temperature-responsive element being positioned for encounter with each other in the movement of the first mentioned movable element due to engine pressure, and the movement of the second mentioned movable element due to rise of temperature beyond a predetermined degree.

6. In an engine having a circulatory cooling system comprising a radiator provided with means for regulating atmosphere access to the exterior of the radiator, and mechanical connection for operating said regulating means; a temperature-responsive element comprised in said connections mounted in position to be substantially affected by the temperature of the circulatory cooling system, a device comprising an expansible and contractible chamber operatively associated with a cylinder of the engine served for access of fluid pressure from the cylinder to said chamber, said chamber having a part movable by said fluid pressure, and a part connected for movement with the temperature-responsive element into and out of position for completing mechanical connection between the fluid-pressure-actuated part and the regulating-means-operating connection.

In testimony whereof I have hereunto set my hand at Chicago, Illinois, this 13th day of February, 1929.
